UNITED STATES PATENT OFFICE.

HARRY C. COOPER, OF CHICAGO, ILLINOIS.

MOLDING-MACHINE SPRUE MECHANISM.

SPECIFICATION forming part of Letters Patent No. 632,245, dated September 5, 1899.

Original application filed December 19, 1898, Serial No. 699,720. Divided and this application filed June 7, 1899. Serial No. 719,746. (No model.)

To all whom it may concern:

Be it known that I, HARRY C. COOPER, a citizen of the United States, residing at Chicago, county of Cook, State of Illinois, have 5 invented a certain new and useful Improvement in Molding-Machine Sprue Mechanism; and I declare the following to be a full, clear, and exact description of the invention, such as will enable others skilled in the art to which 10 it pertains to make and use the same, reference being had to the accompanying drawings, which form a part of this specification.

My invention has for its object the production of mechanism for forming the sprue-ori- 15 fices in the cope portion of a sand mold and also the production of mechanism to produce the pressure in the runner-box of the cope portion of a sand mold.

The apparatus shown in this application is 20 applicable more particularly to the molding-machine forming the subject-matter of my concurrently-pending application filed December 19, 1898, Serial No. 699,720, of which this application is a division. In the said ap- 25 plication is provided mechanism for carrying the pattern or patterns into the flask from below, while above the flask is located stationary pressure mechanism, the compression of the sand taking place between the patterns and 30 said stationary pressure mechanism. My present invention relates particularly to this stationary pressure mechanism and to what I will term "sprues" for forming the sprue-holes. Of course, technically speaking, the 35 sprues are part of the casting, and the parts which form the sprue-holes in the mold are not sprues; but commonly in foundry practice the pins employed to make the sprue-holes are called "sprues," and I will so term them 40 throughout my present application.

The invention consists in a combination of devices and appliances hereinafter described and claimed.

In the drawings, Figure 1 is a vertical section through the apparatus constituting my invention. Fig. 2 is a cross-section through the plunger on the line 2 2 of Fig. 1. Fig. 3 is a cross-section through the plunger with the sprues removed. Fig. 4 is a detail illustrating the construction of the plunger-sprues. Figs. 5 and 6 are details illustrating the plun-

ger and sprue-elevating mechanism. Fig. 7 is a detail of the end of the sprue, illustrating a variation. Fig. 8 is a plan view of one of the sprue-frames with parts broken away. 55 Fig. 9 is a longitudinal section of the same on the line 9 9 of Fig. 8. Fig. 10 is a longitudinal sectional view on the line 10 10 of Fig. 8. Fig. 11 is a section on line 11 11 of Fig. 8. Figs. 12, 13, and 14 are vertical sec- 60 tions of the sprue, showing it in different positions. Fig. 15 is an elevation of the upper end of the sprue-casing. Fig. 16 is a plan view of the same. Fig. 17 is a detail view of the sprue-engaging mechanism. Fig. 18 65 is a side elevation illustrating the sprue-tripping mechanism.

In carrying out the invention, A represents a suitable casing supported in any suitable manner—as, for instance, by the standard A'. 70

B represents what I will call the "pressure-plate."

As stated above, the mechanism described in this application is to be used in connection with pattern mechanism which moves upward 75 and compresses the sand between it and the plate B. I will first describe the mechanism for obtaining a pressure in the runner-box of the cope portion of the flask and for forming the sprue-holes therein. 80

B' represents a suitable opening in the pressure-plate, through which the plunger drops, this opening being located above the runner-box of the flask. Extending up from the pressure-plate B' is a casing A², and carried 85 by this casing is a plunger-casing A³. Within this casing is a plunger C, made hollow, as shown, and its upper end is provided with guides C', traveling in guideways A⁴ on the interior face of the casing A³. Working ver- 90 tically within the plunger C is a fitting D, having three arms which extend through the slots C² in the plunger to the outside of the same. Around these slots the face of the plunger is slotted, as at C³. Carried by each 95 arm of the fitting D is a long tube D', each one constituting a sprue. Each of these sprues is hollow and is provided on its lower end with a diaphragm D², having a restricted orifice D³. On the fitting D is a piston D⁴, and 100 in the lower end of the plunger is a dash-cup C⁴, which the piston enters, and thus cushions

the sprues when they fall, as hereinafter explained. Within the casing A³ and surrounding the piston is a spring C⁵, adapted to cushion the descent of the plunger when it drops, 5 as hereinafter described. Engaged to the lower end of the casing A³ is a ring A⁵, constituting a bearing-ring for the lower end of the plunger as it moves vertically, and constituting also a stripping-plate, through which 10 the sprues and plunger strip when they are withdrawn from the mold. Supported by the upper end of the casing A³ is a plate E, having a bearing E', in which is located what I will term a "crank-spool." Extending through 15 the spool E² is a shaft E³, having on its end a beveled gear E⁴, which meshes with the beveled gear E⁵ on the vertical shaft E⁶. On the end of the spool E² is a disk E⁷. On the end 20 of the shaft E³ are a crank-arm E⁸ and two laterally-extending arms E⁹ E¹⁰. Pivoted to the crank-arm E⁸ is a pitman E¹¹.

E¹² is a fitting traveling on the guide-rods E¹³, and the lower end of the pitman E¹¹ is pivoted to this fitting E¹². Located in this 25 fitting is a vertical rod E¹⁴, capable of turning on its vertical axis, with a spring E¹⁵ for keeping it normally in the position desired. On the lower end of this rod is an arm or foot E¹⁶ and on the upper end another arm E¹⁷. 30 On the sprue-fitting D is a vertical stem D⁵, having its face notched, as at D⁶, in which the foot E¹⁶ engages. On the face of the disk E⁷ and at a distance of ninety degrees from each other are two stops E¹⁸ E¹⁹, with which the 35 arms E⁹ E¹⁰ respectively contact during the operation. Engaged to the crank-arm E⁶⁰ of the crank-spool E² is a pitman E²⁰, the lower end of which is pivoted in the plate E²¹. This latter plate slides vertically in the plunger- 40 casing and is provided with guides E²², similar to those on the plunger. Pivoted in the plate E²¹ is a beveled catch E²³, adapted to engage over the end E²⁴ of the plunger. Extending through the casing A³, above the plate 45 E²¹, is a lever F, said lever being engaged to a vertical rod F'. This rod extends down to a point inside the casing, where it is provided with an arm F². Pivoted to the arm is a rod F³, which extends over and is pivoted to a 50 vertical arm F⁴ on the shaft F⁵. When the shaft F⁵ is partially revolved, it will revolve the vertical rod F' and throw the arm or lever F against the arm E¹⁷ on the rod E¹⁴, and this will tilt the foot E¹⁶ out of the notches D⁶ in 55 the stem of the sprue-fitting and allow the sprue-fitting and its accompanying sprues to drop where they are cushioned by the dash-pot C⁴, as previously explained. Extending also through the casing A³, adjacent to the 60 catch E²³, is a lever F⁶, adapted when tilted into the casing to strike the catch E²³ and release the plunger. This lever F⁶ is engaged to a vertical rod F⁷, on the lower end of which is an arm F⁸. Engaged to this arm by a slotted bearing F⁹ is a rod F¹⁰, which extends over and is pivoted to a vertical arm F¹¹ on the shaft F⁵. Thus when the shaft F⁵ is revolved 65

it first acts through the rod F³ to release the sprues, but because of the slotted bearing the plunger will not be released until the end of 70 the slot is reached. The plunger is then released and drops down, being cushioned by the spring C⁵. When the sprues drop down, each one engages over a knob or projection M on the pattern M', which substantially fills 75 the hollow end of the sprue, so that in addition to the dash-pot C⁴ the sprues are cushioned by the air contained in the space between the end of each sprue and the restricted orifice D³. The sprues will gradually settle 80 down to their places on the pattern, the plunger will drop down into the runner-box, and as the pattern moves upward to compress the sand the sprues and plunger will gradually be carried back. 85

In Fig. 10 at G, I have illustrated the vent-pins; but as these pins have nothing to do with the claims of the present case I will merely mention them incidentally. The same board, however, which carries the vent-pins 90 is provided with what I will term "auxiliary sprues," so that in case the plunger and its accompanying sprues, which I have just described, are not used, but several independent molds are being formed in the same flask, 95 the sprue-holes will be properly formed in the mold. I will now describe these auxiliary sprues.

In the pressure-plate B is a series of orifices which when the auxiliary sprues are 100 not used are filled by plugs B². When the auxiliary sprues are used, the orifice in the pressure-plate through which the sprue passes is provided with a tapered nipple or bearing B³. In the frame H (which also constitutes 105 the frame for holding the vent-pins) at the points where it is desired to locate the auxiliary sprue I provide orifices H' and a vertical tube or casing H², which is screwed into the plate H. 110

H⁴ is a tube constituting a sprue, and on its upper end is a ring H³ to form a guide for the sprue in its vertical movement through the tube H². It also forms a shoulder, by means of which the sprue is held in its upper position. On the interior of the sprue H⁴ is a shoulder H⁵, and threaded into the cap H⁶ of the tube H² is a fitting H⁷ with a vertically-movable stem H⁸ therethrough and a spring H⁹, one end bearing on the end H¹⁰ 115 of the stem H⁸, while the other end bears on the adjustable fitting H⁷. Journaled in the bearings or lugs H¹¹ of the tube H² is a rod H¹², and engaged to this rod is a door H¹³, adapted to fill an opening in the side of the 120 tube H² and having its interior face notched or provided with a series of beveled catches H¹⁴. The shoulder H³ on the upper end of the sprue engages on one of these catches H¹⁴ and the sprue is held up thereby, a spring 125 H¹⁵ keeping the parts in engagement until intentionally released. Adjustably keyed to the rod H¹² is an arm H¹⁶. 130

Journaled in the casing A, along the side

thereof, is a shaft J, having an upwardly-extending arm J', connected by the rod J² with the arm J³ on the shaft F⁵. On the opposite side of the casing is another shaft J⁴, having an upwardly-extending arm J⁵, connected by the rod J⁶ with an upwardly-extending arm J⁷ on the shaft F¹². The shafts F⁵ and F¹² are each provided with a depending arm F¹³, (shown by dotted lines, Fig. 1,) and the two arms are connected by a rod F¹⁴, so that the partial revolution of any one of the shafts J, J⁴, F⁵, or F¹² will revolve the others. On the rods J² J⁶ at desirable intervals or points I locate depending arms J⁸, and these arms striking the arms H¹⁶ revolve the rods H¹², tilt the doors H¹³ out, and thus release the sprues, which drop down onto the pattern, the springs H⁹ starting each quickly in its descent.

From the above description it will be seen that the sprues can be located at any point desired, since the arms J', J³, J⁵, and J⁷ can be adjusted at any desirable points along their respective shafts, and the depending arms J⁸ can be located or adjusted to any point along their respective rods and their number increased or decreased, as desired. So also the orifices for the sprues through the sprue-frame and pressure-plate can be made at any desired points. On the shaft F³ is an arm F²⁰, (shown by dotted lines, Fig. 1,) and depending therefrom is a rod F²¹.

It will be seen from the above description that by a movement of the rod F¹² the shafts J, F⁵, F¹², and J⁴ will be moved and the auxiliary sprues, plunger-sprues, and the plunger will all be dropped automatically.

I will now describe the mechanism for returning the parts to their normal positions.

On each auxiliary sprue-frame are guides H¹⁷, adapted to travel in guideways on the inner face of the casing A and guide the sprue-frame H vertically. This frame is suspended from pitmen H¹⁸, engaged to cranks H¹⁹ on the shaft H²⁰, the parts being duplicates on each side of the plunger. So also the shafts H²¹ H²⁰ are connected up in any suitable manner by means of gears T T' T² T³, so that they will revolve together. On the shaft H²⁰ is a suitable gear H²², (shown in Fig. 1,) which meshes with another gear H²³ on the shaft H²⁴. On this same shaft H²⁴ is a beveled gear H²⁵, which meshes with a beveled gear H²⁶ on the vertical shaft E⁶. Now by revolving the shaft H²⁰ from any suitable source of power the frames H will be thrown to their lower position by cranks H¹⁹. At the same time the shaft E⁶ will be revolved, and this will revolve the shaft E³. This will bring the arm E⁹ in contact with the shoulder E¹⁸ on the spool E² and will throw the pitman E²⁰, and consequently the plate E²¹, down to its lower position. At the same time the revolution of the shaft E³ has carried the fitting E¹² down to its lower position. Now as the pattern parts move upward the plunger and its accompanying sprues, or in case of the auxiliary sprues then the latter, will be carried up so long as the

parts continue to advance. By the time the mold has been formed the plunger and sprues have been elevated high enough so that the respective engaging devices can engage them. In the case of the plunger, however, it is desired that it shall be arrested in its upward movement in order to properly compress the sand in the flask runner-box. This is accomplished by means of the plate E²¹, which when it is lowered forms an abutment against which the upwardly-moving plunger strikes and by which it is stopped. In order that the height at which the plunger is arrested may be regulated, I provide on the upper end of the plunger the adjustable ring E²⁷, threaded onto the exterior of the plunger. We will now assume that the mold has been formed and we are ready to withdraw the parts. A revolution of the shaft H²⁰ in the opposite direction causes the cranks H¹⁹ to elevate the frames H, and this causes the sprues H⁴ to strip through the nipples B³. At the same time it revolves the shaft E⁶, and consequently the shaft E³, and elevates the fitting E¹², and this draws the sprue-fitting D upward, and this strips the plunger-sprues past the plunger and ring A⁵. By the time the shaft E has made a quarter-turn and thus stripped the sprues the arm E¹⁰ comes in contact with the shoulder E¹⁹ and revolves the spool E², and this draws the plunger upward, stripping it through the plate A⁵. I desire at this point to call attention to the lower end of the plunger and to the shape also of the under surface of the ring A⁵. The lower end of the body of the plunger is tapered, as at C¹⁰, and adjacent to the points where the plunger-sprues slide past the end of the plunger the latter is beveled or tapered, as at C¹¹, the result being that when the mold is formed the sprue-orifice formed by the body of the plunger is tapered. The upper end of each sprue-orifice formed by the plunger-sprue is tapered, so that the molten metal will readily enter the sprue-holes, and at the same time a sufficient head of metal will be provided in the sprue-opening to insure the metal entering all the parts of the mold. The under surface of the ring A⁵ is made concave, as at A¹⁰, with a depending flange A¹¹, so that when the mold is formed there will be the rounding surface of the upper end of the sprue-hole to facilitate the direction of the molten metal without having any corners liable to break. If, however, the depending flange were not provided as the sand was forced up against the ring A⁵ during the operation of forming the mold, the sand would be forced out laterally against the side of the runner-box. This is objectionable. Consequently the flange A¹¹ is provided to obviate it.

I have heretofore called attention to the fact that the sprue was hollow and that the restricted orifice D³ allows the air to gradually escape from the lower end of the sprue, and thus allow the sprue to gradually settle onto the pattern. This orifice D³, as well as the

orifice H^20 in the diaphragm H^5 , performs another function. They permit the air as the sprue is withdrawn from the pattern to move down onto the face of the pattern, and thus 5 destroy any vacuum which might otherwise be present and break the mold as the sprues are withdrawn.

It will be seen from the above description that when the plunger is down it, together 10 with the ring A^5 , constitutes a portion of the pressure mechanism, or rather the pressure-plate, and that when the plunger is moved back upward until its upper end strikes the plate E^{21} a solid pressure-plate is formed for 15 all parts of the flask, including the runner-box. It will be observed that the end of each sprue is tapered, as at K , so that when the mold is formed and the metal poured the sprue on the casting formed by the sprue-hole will 20 be united to the casting by a very thin edge and can be easily knocked off without carrying the metal of the casting with it. In Fig. 7 I have shown a slight variation in the shape of the end of the sprue. In this case one side 25 is tapered, as at K' , while the other side is straight, as at K^2 . The reason for this is as follows: Heretofore in pouring the metal to form the castings the metal entering through the sprue-hole of the mold has been caused 30 or permitted to strike the cores or other projecting parts of the mold and soon wear or melt them away. Now by tapering one side of the sprue-hole former, as shown in Fig. 7, and leaving the other side straight, and by 35 turning this tapered side to a point adjacent to the core or other projecting parts which it is desired to have the molten metal void, an inclined end is formed in the sprue-hole, so that when the metal is poured the inclined 40 surface throws the metal away from the part which it is desired to protect.

What I claim is—

1. In a molding-machine a movable sprue and a cushion to receive the sprue at the end 45 of its movement, substantially as described.

2. In a molding-machine a vertically-movable sprue and mechanism for engaging it in its upper or normal position, mechanism for releasing said engaging mechanism to allow 50 the sprue to drop and a cushion to receive the blow of the descending sprue, substantially as described.

3. In a molding-machine a vertically-movable sprue, mechanism for engaging the said sprue in its upper or normal position, mechanism for releasing the sprue from said engaging mechanism and allow it to drop, a plunger or piston carried by the sprue and a dash-pot adapted to receive said plunger, 55 substantially as described.

4. In a molding-machine the combination with a projection arranged to receive a sprue of a vertically-movable sprue having its lower end recessed to fit said projection when in its 60 lower position and a restricted orifice leading from said recess to allow the air to gradually escape from said recess and thus per-

mit the sprue to settle against said projection, substantially as described.

5. In a molding-machine a vertically-movable sprue; mechanism for engaging said sprue in its upper position; mechanism to release the sprue and allow it to drop and vertically-reciprocating mechanism for moving the sprue-engaging mechanism down to 75 engage the sprue and then to elevate it together with the sprue, substantially as described.

6. In a molding-machine, the combination with a vertically-movable pattern and its supporting mechanism, of a vertically-movable sprue adapted to drop down and rest on the pattern mechanism and to be carried up by the upward movement thereof, substantially as described.

7. In a molding-machine, the combination with a vertically-movable pattern and its supporting mechanism, of a vertically-movable sprue adapted to drop down and rest on the pattern mechanism and to be carried up by the movement thereof, and mechanism disengaged from said sprue when in its lower position and adapted to engage the sprue when it is moved up by the pattern mechanism and carry it thence to its maximum height, substantially as described.

8. In a molding-machine a vertically-movable sprue provided with a series of notches and a spring-catch to engage said notches and hold the sprue in its upper or normal position, substantially as described.

9. In a molding-machine a vertically-movable sprue provided with a series of notches, a spring-catch to engage said notches, a vertically-movable fitting carrying said catch 105 and mechanism for moving said fitting vertically, substantially as described.

10. In a molding-machine a vertically-movable sprue provided with a series of notches, a spring-catch for engaging said notches, a vertically-movable fitting carrying the catch, a crank-shaft and a pitman connecting the crank-shaft and fitting to raise the sprues, substantially as described.

11. In a molding-machine, the combination with the plunger, a fixed ring through which the plunger slides and one or more sprues sliding along the face of the plunger, of mechanism for first stripping the sprues through the plunger and then stripping the plunger 115 through the fixed ring, substantially as described.

12. In a molding-machine, the combination with one or more sprues adapted to enter the runner-box of the flask, of a plunger adapted 120 also to enter said runner-box, said sprues sliding in recesses in the face of the plunger and mechanism for first stripping the sprues through the plunger and then withdrawing the plunger, substantially as described.

13. In a molding-machine the combination of a vertically-movable hollow plunger, of a sprue-fitting working in said plunger and provided with arms extending through slots in

the face of the plunger and a sprue attached to each of the arms on the exterior of the plunger, substantially as described.

14. In a molding-machine, the combination with a plunger and one or more sprues, said plunger and sprues being vertically movable, of a crank-shaft carrying mechanism to engage the sprues, a crank-sleeve surrounding the shaft and carrying mechanism to engage the plunger and stop mechanism between the crank-shaft and crank-sleeve whereby a partial revolution of the shaft withdraws the sprues and the continued revolution thereof withdraws the plunger, substantially as described.

15. In a molding-machine, a plunger adapted to enter the runner-box and one or more sprues, the lower end of which projects into the runner-box below the end of the plunger, the surface of said sprues bearing against the surface of the plunger and the end of the plunger adjacent to the sprues being tapered whereby a tapered surface is formed in the mold adjacent to the sprue-hole, substantially as described.

16. In a molding-machine a vertically-movable sprue and a spring-catch for holding it in its upper position, one of said parts being provided with a series of engaging surfaces whereby the sprue can be engaged at variable heights, substantially as described.

17. In a molding-machine the combination with the vertically-movable frame and vertically-movable pattern mechanism of a vertically-movable sprue adapted to drop down and rest on the pattern mechanism and to be carried up by the movement thereof, mechanism disengaged from said sprue when in its lower position and adapted to engage the sprue when it is moved up by the pattern mechanism and carry it to its maximum height the engaging surfaces between the sprue and its engaging mechanism being in vertical series whereby the sprue may be engaged at variable heights, substantially as described.

18. In a molding-machine the combination of the plunger and mechanism for engaging it in its upper position, said plunger adapted

to drop and enter the runner-box, one or more sprues; mechanism for engaging the latter in their upper position and tripping mechanism connected with both the plunger and sprue-engaging mechanism, the engagement between said tripping mechanism and the plunger-engaging mechanism being slotted whereby a movement of the tripping mechanism will first strip the sprues and then the plunger, substantially as described.

19. In a molding-machine, a sprue, mechanism for engaging it in its upper position, said sprue adapted when released to drop down and a spring bearing on said sprue when engaged in its upper position and adapted to start said sprue quickly on its descent when released, substantially as described.

20. In a molding-machine the combination with a pressure - plate through which the sprues movably pass, of a vertically-movable frame having a series of sprues; mechanism on the frame for engaging said sprues; mechanism for releasing said engaging mechanism to allow the sprues to drop, said sprues carried upward by the upward movement of the frame, substantially as described.

21. In a molding-machine the combination with a vertically-movable frame, of a series of detachable sprues; mechanism on the frame for engaging each sprue independently of the other and holding it in its upper position, adjustable mechanism for releasing each sprue at the time desired and allow it to drop; mechanism for moving the frame down to engage the sprues, said sprues carried up by the upward movement of the frame, substantially as described.

22. In a molding-machine the combination with a vertically-movable frame of a series of sprues carried thereby and a spring-catch for each sprue carried by the frame, each of said catches having a series of engaging surfaces to engage the sprue substantially as described.

In testimony whereof I sign this specification in the presence of two witnesses.

HARRY C. COOPER.
